UNITED STATES PATENT OFFICE

2,469,143

APPAREL-HANGER CABINET

Michael Ascherl, Lorain, Ohio

Application September 29, 1945, Serial No. 619,287

5 Claims. (Cl. 312—174)

1

This exemplification of my invention pertains to an apparel-hanger cabinet or more specifically to a dust-tight cabinet provided with a door or doors and a hanger or hangers for suspending neckties; a door and a hanger, besides being each movably attached to the cabinet, being themselves interconnected, as by a link articulated with each, whereby to move in unison in response to manipulation of an actuating structure.

The objects of my origination, in addition to those evidenced by the foregoing paragraph, are the attainment of compactness, facility and reliability of operation of either an opening or of a closing manual actuation, due economy of manufacture, as prescribed respectively by the utilitarian purpose of a domestic appliance and by the hope for its marketed introduction.

Adverting to the drawings:

Figure 1 is a front elevation of a necktie cabinet embodying my invention.

Figure 2 is a front elevation with a front mirror removed and a pair of lateral doors in open position.

Figure 3 is a horizontal view, taken substantially on line 3—3 of Figure 2, looking downward.

Figure 4 is a view substantially on line 4—4 of Figure 1, looking downward.

Figure 5 is a horizontal view, taken substantially on line 5—5 of Figure 2, looking downward.

Figure 6 is a view corresponding to Figure 5, but with certain parts shifted to alternative positions.

Figure 7 is an enlarged perspective view of a roller carriage comprising necktie hangers.

Figure 8 is an enlarged vertical section viewed on line 8—8 of Figure 5.

Figure 9 is a view corresponding to Figure 8, but showing certain parts in altered positions consequent to a shifted position of the door-actuating mechanism, taken on line 9—9 of Figure 6.

A cabinet includes a bottom 1, a top 2, a front mirror 3 attached to the top and bottom, a narrow panel 4 therebelow, which may have ornaments at each side as indicated by the numerals 5, a rear wall 6, provided near its top with a pair of spaced suspension eyelets 7, and side-forming doors 8 and 9 which are respectively carried by a pair of hinges 10 and 11 which are also affixed to opposite edges of the rear wall 6. Near the bottom of its inside, the door 8 may conveniently carry a pincushion 12 while the door 9 may be provided in a similar location with a shelf 13 for collar buttons or other fasteners.

2

Secured in any feasible manner, as by brazing, riveting or spot welding, to the top 2, is an obtuse-angled track, rail or guideway 14 which is most clearly illustrated in Figure 3. The purpose of the track 14 is to prescribe the lines of travel, reciprocably, of a pair of U-shaped roller carriages 15, one of which is clearly shown in Figure 6. Each carriage comprises a pair of upper, relatively spaced and stud-supported rollers 16 located, one pair on the inner side of each of the two upstanding arms of the U-shaped formation. Therebelow, at the inner ends respectively of a cross rod 17, are a pair of opposed rollers 18 which are suitably spaced below the rollers 16 to permit interpositioning of the track 14 whereby to ease and steady the reciprocating travel of the two convergent or divergent carriages when actuated as later to be described. Extending from the interjacent section of each carriage 15 are a plurality (three shown) of parallelly disposed necktie hangers 19 which are preferably fashioned with upturned extremities 20 intended to prevent neckties 21 which are folded thereover from slipping off.

As appears to view in Figure 3, the lower side of each carriage is connected with a door; for instance, with the left door 8 by means of a link 22 which is articulated at 23 with that door and at 24 with one of the carriages. To be observed in Figure 3 is the position of the left carriage when its connected door 8 is open and in Figure 4 the different position of the carriage on the right side when its door 9 is closed.

The door and carriage-hanger actuating mechanism is next to be described. Passed through an opening provided in the panel 4, is a push or pull rod 25 which is fashioned near its outer end with a notch 26 and at its outer extremity with a knob 27. Observation of Figures 4 and 7 will disclose a coil spring 28 surrounding the rod 25 within the confines of the lower part of the cabinet and that the ends of the spring 28 are buttressed between a depending bracket 29 attached to an inverted U-shaped bracket 29a and a rod-affixed plate 30 which is fixed to a depending flange at the opposite end of the bracket. Movement is imparted to the rod 25, either inwardly by exertion manually of a push against the knob 27 to compress the spring and simultaneously to close the two doors 8 and 9; or outwardly in response to the pressure of the spring whereby to open both doors. This coaction is accomplishable by the connections illustrated and to be now explained. Articulated, by means of a rod-attached pin 25a which travels

in a slot in the bracket 29a, as a kind of dual toggle, is one pair of interconnected links 31 and 32 and another pair of links 33 and 34, the free end of the link 31 being pivotally connected, end to end, with the link 35 and the free end of the link 33 likewise being pivotally connected, end to end, with a link 36. The links 32 and 34 are turnably connected with a pin 25b which is passed through the bracket 29a. Opposite ends of the links 35 and 36 are pivotally connected at 37 and 38 with the doors 8 and 9 respectively. In consequence, when the rod has been shoved inwardly to the position which it is shown to occupy in Figure 5 both doors will have assumed their closed positions. The arrangement is desirably such that an inward push exerted upon the knob 27 will draw the doors to their closing positions, whereas, an outward pull upon the knob will open both doors simultaneously and coincidently project the hangers 19 beyond the confines of the cabinet whereby to facilitate observation of the supported neckties and removal of the one selected.

The location of the notch 26 along the rod 25 should be so contrived that when the doors are in their substantially fully closed position, a slight downward pressure on the rod will cause a section of the margin of the hole in the panel 4, through which the rod extends, to occupy the notch 26 whereby to maintain the doors in their closing positions against the pressure exerted by the spring 28, as disclosed in Figure 5. An upward pressure on the rod 25 will release the catch means just explained and permit the spring to open both doors and to withdraw the carriages and their hangers from the cabinet until the toggle and link mechanism assumes the relationship of its parts which appears to view in Figure 4, whereupon some particular necktie (or other suspended article) may be selected and removed.

It is to be realized that the scope of my invention comprehends many equivalent constructions and that the graphical showing and the specific description are merely exemplifications of features of design or of feasible mechanical embodiments and arrangements within the scope of the granted claims.

I claim:

1. In a necktie cabinet, the combination of a frame comprising spaced front and rear walls and an open side, a lateral door hinged to an edge of the rear wall of said frame at said side, a necktie holder, means including a link whereby said holder is movably connected with said frame and also with said door and mechanism including a handle extending through said front wall for operating said door, said mechanism including means adapted to function at one near limit of movement of said door for locking the parts in position.

2. In an apparel cabinet, the combination

of a frame having a fixed front wall and having a rear portion spaced from said wall, an upper, interior guideway on said frame, a pair of doors hinged to opposite vertical edges of said rear portion and each adapted to close one of the sides of the frame, a pair of suspension holders having means whereby they are movably connected with said guideway and with said doors respectively and means including a part extending through said front wall and connected with both doors for simultaneously operating said doors and holders in unison.

3. In combination, a cabinet comprising front and rear walls, side-forming doors hinged to opposite edges of said rear walls respectively, a pair of rearwardly convergent tracks within said cabinet, a necktie holder mounted to travel on each of said tracks, separate means connecting said holders with said doors respectively and toggle mechanism for actuating said doors and comprising connections with the latter and further comprising an element extending through said front wall.

4. In a cabinet having a mirrored front wall and a rear wall spaced therefrom, a pair of side doors hinged to said rear wall, converging tracks mounted within said cabinet, a pair of carriages each comprising a hanger movable along one of said tracks, connections between said carriages and doors respectively and mechanism for actuating said doors and hangers in unison.

In a cabinet, a door hinged thereto, a track mounted within said cabinet near its upper end and having a section oblique with reference to the walls thereof, a carriage connected with said door and comprising a hanger, said carriage being movable along said track, and spring-controlled mechanism connected with said door for actuating it and said carriage in unison in one direction, said mechanism including a releasable catch for holding it against the action of its spring.

MICHAEL ASCHERL.
